H. C. HERR.
AUTOMATIC HOSE COUPLING.
APPLICATION FILED MAR. 4, 1914.

1,118,129.

Patented Nov. 24, 1914.

UNITED STATES PATENT OFFICE

HERBERT C. HERR, OF DALLAS, TEXAS.

AUTOMATIC HOSE-COUPING.

1,118,129.

Specification of Letters Patent. Patented Nov. 24, 1914.

Application filed March 4, 1914. Serial No. 822,264.

To all whom it may concern:

Be it known that I, HERBERT C. HERR, citizen of the United States of America, residing at 2617 Birmingham street, Dallas, 5 Texas, have invented certain new and useful Improvements in Automatic Hose-Couplers, of which the following is a specification.

My invention as specified relates to new and useful improvements in automatic hose 10 couplers.

The primary object of the invention is to provide an automatic hose coupler of such a character that will be economical of time consumed in coupling up the joints of hose, 15 and highly adaptable for use on all forms of hose used for the conveying of water.

A further object of the invention is to provide an automatic coupler of the character described which may be coupled directly 20 to the present form of street fire plug and expeditiously used by the fire departments.

Finally the object of the invention is to provide a device of the character described 25 that will be strong, durable and efficient, simple and comparatively inexpensive to construct, also one in which the several parts will not be liable to get out of working order.

With the above and other objects in view the invention has relation to certain novel 30 features of construction and operation, an example of which is described in the following specification and illustrated in the accompanying drawings, wherein:

Figure 1 is a view of a street fire plug showing the automatic coupling attached thereto and communicating with the fire 35 hose. Fig. 2 is a view of the female coupling attached to the hose. Fig. 3 is a view of the male coupling attached to the hose. Fig. 4 is a view in front elevation of the female coupling showing the open end 40 which receives the male coupling. Fig. 5 is a view in front elevation of the male coupling showing the end adapted to be introduced into the associated coupling. Fig. 6 is a longitudinal sectional view of the female coupling. Fig. 7 is a sectional view 45 of the male coupling the section being taken upon the line $x-x$ of Fig. 5. Fig. 8 is a sectional view taken upon the line $y-y$ of Fig. 6.

Referring now more in particular to the 50 drawings wherein like reference characters designate similar parts throughout, the nu-

meral 1 designates an ordinary type of street fire plug to which is attached, through the automatic coupler, the hose 2.

A description will first be given of the 60 female coupling member, reference being had to the several views of said member. This element of the device, as in the standard type and form in present use, consists of two elements or parts so associated together that one part may swivel upon and about the other without danger of leaking water from the high pressure passed through the fire hose.

Referring particularly to the Figs. 2, 4, 6 and 8 of the drawings, the numeral 3 designates a cylindrical shell member which substantially forms the body of the female coupling. A swivel member 4 of substantially the same proportions as the body member 3 is provided and forms an important element of the female member of the coupling device. The member 4 has formed on its interior periphery and near one extremity an inwardly projecting concentric ring 5 70 provided with an integrally formed annular flange member 6. A concentric ring 7 is integrally formed on the interior periphery, adjacent to the swivel member, of the body member 3. The flange member 6 is spun 75 and turned down over the face of said ring 7 as designated by the numeral 7^a. This substantial association of the two elements 3 and 4 forms, as previously mentioned, a swiveled union or connection between the 80 two said members. It is thus seen that one of the members 3 or 4 may be turned about its axis without affecting the other. A packing ring or washer 8 of rubber or other suitable material is retained in the coupling 85 and lies in contact with the spun flange 7^a and against the inner periphery of the body member 3. This packing washer is adapted to form a water and air tight joint between the 90 couplings when the other element of the coupling, yet to be explained, is introduced and locked in the body member 3. The swivel member 4 is adapted to receive and firmly join to the hose. To this end, 95 angular corrugations 9 are provided on the 100 interior periphery of the swivel member. The hose is retained by expansion rings (not shown) tightly against and in the 105 grooves of the corrugations. This is the standard method of joining up the hose and 110 coupling members.

Rectangular recesses 10 are formed in the

inner periphery of the body member and have their longest sides lying adjacent and parallel to the front face of the body member. Ratchet pawls 11 with ratchet heads 12 are pivotally mounted upon pins 14 within the recesses 10. Coiled compression springs 15 are retained between the walls of the recesses and against the outer extremities of the pawls. These compression springs keep the ratchet heads 12 inwardly displaced. Buttons 16 are mounted in apertures in the body member and have integrally formed upon their inner extremities shoulders 17. The buttons lie in contact with the extremities of the pawls 11. The shoulders confine the button in the body member preventing them from coming out. The parts and elements just described are preferably in pairs and arranged diametrically opposite each other.

A pair of diametrically opposed grooves 18 is received in the inner periphery and adjacent to the front face of the body member. The said grooves are helically formed 25 in direction with respect to the axis of the female member. A passage 19 lies parallel to the axes and opens into the outer face of the body member, opening and communicating said grooves 18 to the exterior, adapting said grooves to receive elements herein 30 after referred to.

A concentric exterior ring 20 bounds the periphery of the body member 3 which forms a protective body to the coupling member, preventing the possible denting or defacing of the front face of the body member when same is roughly used on pavements and curbs. A pair of diametrically opposed cylindrical lugs 21 are integrally formed 40 on the outer periphery of the member 3. These lugs receive the spanner wrench which is used by the fireman in tightening the joint after the automatic coupling is made.

A description will now be given of the male element of the coupling; also a description of the operation, or just how the parts are easily and speedily coupled will be developed.

With particular reference to the Figs. 3, 5, and 7 the numeral 22 designates the cylindrical male element which, when properly associated with the portion just described, embodies the invention herein described.

The extremity or portion 24 has its walls substantially reduced in thickness and is the portion adapted to be introduced into the female coupling. A pair of diametrically opposed radial lugs 27 are integrally formed upon the exterior periphery of the portion 24 of the member 22. Said lugs are rectangular in cross section and have their size and proportion adaptable to register with, enter and engage the passage 19. After the lugs 23 are introduced through the passages 19 65 into the grooves 18, a turn of one of the

members 3 or 22 will cause the lugs 23 to travel in the grooves 18 and draw the portion 24 of the member 22 farther into the member 3 until the face or outer surface of the portion 24 closely contacts and binds the packing washer 8. This forms a water tight joint. Two sets of ratchet teeth 25 are formed upon the outer periphery of the portion 24 of the member 22 and arranged in opposed relation. Scalloped channels 26 are formed adjacent to the teeth and adapted to allow the ratchet heads 12 to drop thereinto when the male member is introduced into the member 3. It is seen that the ratchet head 12 would engage the ratchet teeth 25, but in providing the adjacent scalloped channels the two members are rendered sure and positive in the speedy operation of joining up.

A pair of lugs 21^a are provided and adapted to receive the fireman's spanner wrench used in tightening the joints as previously described. Corrugations 9^a are provided in the inner periphery of the member 22, adapting said member to be joined to the hose in a manner similar to one already described. When the two elements of the coupling are brought together by inserting one in the other, it is seen how the pawls will engage the ratchet teeth and hold the members in locked relation as they are tightened against each other.

Figs. 2 and 3 co-join in the illustration of the manner of coupling or joining up the hose line. The two elements of the coupling are shown in proximate position ready to be thrust one into the other, tightened and locked as previously explained.

The swivel member 4 is of course rendered necessary in the present type of screw and threaded coupling. In my invention the swivel member or any swivel action if desired may be entirely eliminated, in that the hose will easily yield and compensate for the slight turn of one of the elements necessary for coupling and locking of said elements.

Fig. 1 illustrates the adaptability of my invention to the present form of fire plug. The male element or member 22^a is slightly modified in form, by being provided with screw threads instead of the corrugations 9^a, (screw threads not shown) to meet the requirements of the threaded receiver plug 1^a of the street plug. This male member is 12^a permanently provided and fitted to the street plug and when not in use is covered by the female cover plug 27. Said cover plug is also slightly modified in form to meet the requirements extant in the present system of street water plugs. As illustrated said cover plug substantially embodies the element 3 of the female coupling with the swivel portion 4 eliminated and the rear face cast and formed substantially solid and pro- 130

vided with the pentagonal nut head 28 which receives the wrench used in tightening said cover plug on the male element of coupling after the hose has been removed from said 5 fire plug. A chain 28 retains the cover plug to the fire plug.

The scope and intent of the invention is presented to include, embody, cover and anticipate all such changes, modifications, and 10 derivations of form which may arise or be deduced from the generic principle herein delineated and subsequently claimed as is specifically pointed out and claimed in the following:

15 Claim:

In an automatic coupler a female member, a pair of diametrically opposed helical grooves formed in the female member, longitudinal passages extending from the face 26 of the female member and opening into the

helical grooves, a pair of pawls pivoted in the female member, release buttons correlated with the pawls, shoulders formed on said release buttons confining said release buttons to their place, raised lugs adapted to 25 receive the spanner wrench and prevent the release buttons from being released or pressed when dropped upon the ground; a male coupler member, a pair of diametrically opposed lugs formed on said member, 30 spanner wrench lugs, ratchet teeth, and scalloped channels formed on the male member adjacent to the teeth adapted to receive the heads of the pawls.

In testimony whereof, I affix my signature 35 in the presence of two witnesses.

HERBERT C. HERR.
